(57) **CLAIM**

The ornamental design for a snorkel tube as shown and described.

DESCRIPTION

FIG. 1 is an upper front perspective view of a snorkel tube in accordance with the present invention;

FIG. 2 is an upper rear perspective view thereof;

FIG. 3 is a lower left perspective view thereof;

FIG. 4 is a lower right perspective view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

The dashed lines denotes internal structure that forms no part of the claimed design.

1 Claim, 10 Drawing Sheets
